(57) **CLAIM**

The ornamental design for an electrical receptacle component as shown and described.

DESCRIPTION

FIG. 1 is a perspective view of an electrical receptacle component showing our new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof; and

FIG. 7 is a bottom plan view thereof.

The dash-dot broken lines in the drawings depict the bounds of the claim which extends to the dash-dot broken lines but does not include the dash-dot broken lines, while all other broken lines depict portions of the electrical receptacle component that form no part of the claimed design. All broken lines form no part of the claim.

The shade lines in the Figures show contour and do not claim surface ornamentation or treatment.
